UNITED STATES PATENT OFFICE.

NATHANIEL B. ABBOTT, OF BROOKLYN, ASSIGNOR TO THE NEW YORK
BOTTLE CAP AND MACHINE COMPANY, OF NEW YORK, N. Y.

DESIGN FOR A BOTTLE-CAP.

SPECIFICATION forming part of Design No. 24,862, dated November 5, 1895.

Application filed November 30, 1894. Serial No. 530,489. Term of patent 7 years.

To all whom it may concern:

Be it known that I, NATHANIEL B. ABBOTT, a citizen of the United States, and a resident of Brooklyn, in the county of Kings and State of New York, have invented a new and original Design for Bottle-Caps, of which the following is a specification.

In the accompanying drawings, forming a part of this specification, and in which like letters of reference indicate like parts in all the figures, Figure 1 is a plan view, Fig. 2 an edge view, and Fig. 3 a sectional view, of my newly-designed bottle-cap.

The leading features of my design are the following: A cap having a pendent flange provided with a circumferential row of grooves extending in a direction from the top toward the bottom of the flange, an inwardly and downwardly inclined shoulder at the bottom of the flange, a circumferential row of indentations in said shoulder, an annular bead at

the top of the flange, and a slight protuberance on the top of the cap.

A is the cap; B, the pendent flange; C, the grooves in the same; D, the inclined shoulder; 25 E, the indentations in the same; F, the annular bead at the top of the flange, and G the slight protuberance on the top of the cap.

Having thus described my invention, what I claim as new, and desire to secure by Letters 30 Patent, is—

The design for a bottle cap, as herein shown and described.

In testimony that I claim the foregoing as my invention I have signed my name, in presence of two witnesses, this 21st day of November, 1894.

NATHANIEL B. ABBOTT.
